UNITED STATES PATENT OFFICE.

MARSHALL L. SHEPHERD, OF MONTGOMERY, ALABAMA, ASSIGNOR, BY MESNE ASSIGNMENTS, TO UNITED STATES SWITCH COMPANY OF DELAWARE, OF EAU CLAIRE, WISCONSIN.

RAILWAY-SWITCH MECHANISM.

1,275,773.

Specification of Letters Patent. Patented Aug. 13, 1918.

Application filed March 22, 1916. Serial No. 85,917.

To all whom it may concern:

Be it known that I, MARSHALL L. SHEPHERD, a citizen of the United States, residing at Montgomery, in the county of Montgomery and State of Alabama, have invented 5 new and useful Improvements in Railway-Switch Mechanism, of which the following is a specification.

This invention relates to railway switch mechanism for controlling the passage of rolling stock from a main track to a branch track or siding, and vice versa, and particularly to means for preventing what is commonly known as a "split" switch and the dangers to travel resulting therefrom.

One object of the invention is to provide 15 means, controlled by the rolling stock, for positively shifting the switch to its intended position in the event that the switch should be in split position, due to any of the ordinary causes.

Another object of the invention is to provide simple and improved means for throwing the switch and locking the same in thrown position, releasing and automatically closing the switch when the rolling stock passes therethrough, compensating for expansion and contraction, and variations in the range of movement to completely throw the switch, due to spreading of the rails or 25 other causes, and for cushioning the movements of the parts to secure ease of action and prevent damage.

A still further object of the invention is 30 to provide means for normally holding the switch closed for travel over the main line, while permitting travel from the branch line to the main line, and for preventing any accidental locking of the switch in thrown position after being released for closing 35 movement.

With these and other objects in view, the invention consists of the features of construction, combination and arrangement of parts hereinafter fully described and 40 claimed, reference being had to the accompanying drawings in which:

Figure 1 is a top plan view of the rails and switch mechanism at a switch point, showing the switch point locked in normal 45 position for travel on the main line.

Fig. 2 is a similar view, on an enlarged scale, of the rails and parts of the switch mechanism at one side of the track, showing the switch point thrown to open position

and the guard rail shifted and held shifted 55 by a wheel of the rolling stock.

Fig. 3 is a view similar to Fig. 2, showing the rails and parts of the switch mechanism at the opposite side of the track.

Fig. 4 is a sectional view on an enlarged 60 scale taken on line 4-4 of Fig. 2.

Fig. 5 is an enlarged vertical transverse section through the switch throwing and locking means and showing the parts in normal position.

Fig. 6 is a view similar to Fig. 5, showing the parts moved to switch throwing and locking position.

Figs. 7 and 8 are views in elevation of the detector bar as it appears when set for reverse switch adjusting or facing motions.

Fig. 9 is a detail section on line 9-9 of Fig. 7.

Fig. 10 is a view similar to Fig. 8 showing a modified form of detector bar.

Fig. 11 is a view showing a modified form of latch or locking device.

Referring to the drawings, 1 and 2 designate the main line rails, 3 and 4 the branch line or siding rails, and 5 and 6 the switch rails connected for movement in unison by the bridle bar or rod 7, said rails 5 and 6 forming a switch point movable laterally to open and close communication between the main and branch lines. The switch point is 85 self-closing, being normally held in closed position for travel over the main line by means of one or more closing springs 8. Each closing spring is arranged in a cylinder or casing 9 and exerts its energy on a plunger 10 pivotally coupled by a lever 11 and clip 12 to the rail 6. As shown, the lever 11 is pivoted to one of the ties of the roadbed and the parts arranged in such manner as to cause the strong coiled spring 8 to resist 90 movement of the switch point toward the rail 1 in throwing the switch to connect the branch line with the main line, and to subsequently return the switch point, when released for retraction, to normal position in 100 which the main line is maintained in condition for travel over the switch point and communication is closed between the branch and main line.

A spring forming a component part of the switch throwing mechanism 105 is also employed to assist the retracting spring or springs 8, under certain conditions, in returning the switch to normal position, as hereinafter described.

The switch throwing mechanism, which also includes a switch locking mechanism, is arranged at one side of the track structure and in proper proximity to the switch point, and comprises a sliding switch throwing and controlling bar 13 movable between guide members 14 on a bracket plate 15 secured to the tie. This bar is provided with a rearwardly projecting stem 16 and said bar 10 is chambered to telescopically receive a connecting rod 17 coupled by means of links 18 to the adjacent end 19 of the bridle bar 7. The links 17 form a flexible joint between the throw bar and bridle bar which permits 15 relative lateral movement between the two, thus adapting the bridle bar to move with the rails in the contraction and expansion of the latter without causing binding or strain, upon the throw rod or interfering with the 20 operation thereof. The hollow bar 13 is provided with an internal partition or abutment 20 and is closed at its inner end by a plug 21 which forms a stop or abutment in spaced relation to the abutment 20. Inclosed 25 within the casing and surrounding the rod 17 between the abutment 20 and an abutment and tensioning nut 22 is a coiled motion transmitting and retracting spring 23, and on the rod 17 is a fixed stop or contact 30 24 which is normally held by the expanded spring 23 in engagement with the abutment 21, when the parts are in the position shown in Figs. 1 and 5 in which the switch rail 6 abuts against the rails 2 and 4 and the switch 35 point is in normally closed position.

The switch as shown is designed to be automatically opened by the wheels of rolling stock traveling from the branch line into the 40 main line and to be manually thrown to permit the rolling stock to pass from the main line into the branch line, although it is to be understood that any suitable type of means may be employed for automatically throwing the switch by the motion of rolling stock from the main line so that the rolling stock may travel into the branch line, the switch then automatically closing as above described. In the present instance a weighted 45 throw lever 25 is provided which is fixed to a rock shaft 26 and transfers motion to a crank arm 27 which is pivotally connected with the outer end of a reciprocating actuating and controlling bar 28. The inner end 50 of this bar 28 is provided with an inclined or cam surface 29 and with a longitudinal slot 30, which slot receives a retaining and guide pin 31' on a carriage or yoke 31 having upstanding apertured lugs 31^a and 31^b, 55 whereby the yoke 31 is slidably connected with the stem 16. Figs. 5 and 6 respectively show the parts of the switch throwing and locking mechanism and cooperating member of a tripping or releasing mechanism in 60 normal and thrown positions, from which it

will be seen that when the parts are in normal position, as illustrated in Fig. 5, the pin 31' engages the rear wall of the slot 30, while when the switch is thrown as illustrated in Fig. 6, the bar 31 is moved forwardly to a position in which the pin 31' occupies the forward portion of the slot.

The bar 13 is provided with a locking lug or projection 32 having a forward inclined or sloping face 33 and a rear shoulder 34. This lug is adapted for engagement with a depending locking lug 35 upon the forward end of a locking latch or dog 36 pivotally mounted as at 37, upon an upright 38 on the bracket 15 and having a controlling arm 39 provided with a V-shaped detent 40 forming front and rear sloping detent surfaces. The arm 39 passes through and is movable vertically between the arms sides of the upper portion of the lug 31^a which is bifurcated or slotted to receive the lever, and the said arms or sides of this bifurcation or slot are connected by a cross pin 41 providing a detent to coöperate with the lug 40, as hereinafter described. Pivoted to the yoke 31, as at 42, is a clutch member or dog 43 having a weighted controlling arm 44 provided with an inclined shoulder 45 and a hooked engaging or latch arm 46 and formed with a beveled end 47. Pivoted intermediately to the bracket 16 is a trip lever or member 48, one arm of which normally extends across the plate 15 beneath the bar 16 and over the clutch dog 43 is disposed. When the parts are in the normal position shown in Fig. 5 the pin 41 lies against the rear inclined face of the lug 40, the lug 35 is disposed in advance of the locking shoulder 34 of the lug 32, and the surface 29 of the bar 28 engages the shoulder 45 of the dog 43 and holds the weighted controlling arm of said dog upward and the latch arm thereof depressed, which latch arm is disposed below the surface of the bracket yoke 31 and the lever 48, allowing said lever to freely play or move without interference from or disturbing the switch throwing and locking mechanism.

In the operation of the switch, it will be evident from the foregoing that the switch point is normally in the position shown in Fig. 1, the rail 1 being continuous while the sections of the rail 2 are connected by the switch rail 6, the rail 5 lying out of contact with the rail 1, so that travel over the main line may be continuous and uninterrupted. It will be seen also from the foregoing description that the switch rails are free to be moved laterally toward the rail 1, so that the switch will be thrown automatically by the wheels of rolling stock traveling from the branch line into the main line, the switch being automatically returned to normal position when cleared by the wheels. In this

operation the throw rod 17 and bar 19 move forward as a unit to an extent less than the distance between the lug 35 and shoulder 34, the lug 35 riding up on the inclined surface 33 to the highest point of the lug 34, at which time the point will be fully thrown, such movement occurring without any locking action between the sliding sleeve and latch bar 36. It will of course be understood that when the wheels of the rolling stock pass out of engagement with the switch rails the switch will be automatically retracted by the spring or springs 8. In throwing the switch for the passage of rolling stock from the main to the branch line, the lever 25 is moved upward to force the actuating bar forward and the lever is then released and allowed to drop downward to retract and reset said actuating bar, which thereupon remains inoperative until the parts of the switch throwing mechanism are returned to normal position. The forward movement of the bar 28 transfers motion to the yoke 31 through the clutch dog 43, and the bar 13 is moved forward until its shoulder 34 passes in front of the lug 35 of the latch 36, thus locking the bar in projected position. At the same time the pin 41 is carried forward over the rear face of the detent 40, which coacts with the inclined surface 33 to tilt the latch in an obvious manner, and then the pin 41 engages the front inclined surface of the detent 40, thereby permitting the latch 36 to ride into and be held in locking engagement with the thrown bar. In its forward movement the bar 28 compresses the spring 23, which forms a yielding connection and a means to transmit motion between said bar and the rod 17, by means of which motion is transmitted to the switch point to shift it from the main line position shown in Fig. 1 to the branch line position shown in Fig. 2. The degree of switch closing motion of the bar 17 is greater than that necessary to throw the switch, and hence after the switch is thrown the bar will continue to move forward and such forward motion will compress the spring 23 to a greater extent, whereby the switch will be held thrown with augmented spring pressure. The telescopic spring connection between the throw bar and rod also provides a cushioning means to absorb all shocks and jars and protect the throwing and locking mechanism from undue strains, as well as to provide for the crowding of the switch point over toward the rail 1 in the event that the rails should spread, to properly face the point rail 5 against the track rail 1. Furthermore, the spring provides for a variation in the distance of the throw according to the distance between the track rails without strain upon the throwing mechanism. Finally, the telescopic spring connection permits the rod 17 to slide back

without violence or slamming upon the return of the switch to normal position after being thrown. When the parts are in normal position and the point rails are moved over by the wheels of rolling stock passing from the branch line into the main line, the connecting rod 17 and bar 19 will be drawn forward as a unit, as heretofore stated, but to a degree less than the normal distance between the lug 35 and shoulder 34, thus obviating any liability of the switch being locked against automatic closing when released by the wheels of the rolling stock.

It is well known that many accidents are caused by what is known as a split switch, which may be due to spreading of the rails, undue expansion and contraction of parts, looseness of the parts from wear or the accumulation of ice or snow between the switch rails and track rails, preventing the switch rails from having a full degree of closing movement in one or both of its directions of movement. In order to overcome this difficulty I provide means for automatically, under the action of rolling stock approaching the switch from the main line for travel along the main line or passage to the branch line, adjusting the switch point, if not fully thrown or if in a split condition, to properly face the point rails with relation to one or the other of the track rails according to the intended course of travel of the train. In the present instance I have shown two means or sets of devices for accomplishing this result which may be employed alone or in conjunction with each other, and one of which also serves as a means for tripping and unlocking or releasing the switch, when thrown by the switch throwing mechanism, for return to normal position. Arranged alongside of the track rail 1 is a guard rail 49 having the curved end portions 50 for an obvious purpose and mounted for lateral motion toward and from the rail 1. The rail 49 is adapted to be controlled and returned to normal position by spring retracting devices 51 similar in general construction to the spring retracting device 9 for returning the switch point to normal position. These spring retracting devices 51 hold the rail 49 pressed against the track rail 1 in alignment with the point of the switch rail 5. The ends of the rail 49 are connected by clips 52 with bell crank levers 53 and 54 fulcrumed to the ties outwardly beyond the rail 1 and the said bell-crank levers are connected for movement in unison by a rod 55. The bell-crank lever 54 is also connected by a rod 56 with the trip or releasing lever 48 by means of which the latch may be released and the switch returned to normal position after the wheels have cleared the switch, as hereinafter described. A reciprocating bar 57 is fitted to move in a guide way 58 and this bar is pro-

vided with a wedge-shaped controlling cam 59 connected by a coupling connection to the lever 54 so as to advance or retract the cam upon the movements of the guard rail from 5 and toward the rail 1. The coupling connection referred to is of the telescopic spring controlled type and comprises a rod 60 pivoted at one end to the cam and a sleeve 61 pivoted at one end to the lever 54, the opposite end of the rod being provided with a head 62 slideable in the sleeve and a coiled spring 63 being arranged to surround the rod between said head and the free end of the sleeve, by means of which the rod and sleeve 10 are adapted to normally move as a unit, while in the event of any shocks, jars, pressures or undue strains or length of motion falling upon or made by the connection a cushioning action will be established to prevent 15 injury to the parts and to take up any lost play or motion and compensate for variations of travel. The reverse inclined faces of the cam 59 are arranged for coöperation with similar faces of a V-shaped cam 20 or contact member 64 on a controller bar 65 extending under the track and provided with clips 66 which slidably engage the bases of the rails 5 and 6 to allow said rails to expand and contract without shifting said 25 controller bar out of position. When the switch is arranged in normal position for travel on the main line, the point of the rail 6 engages the rail 2 while the point of the rail 5 is spaced from the rail 1 and the 30 cam 59 is in position for its inner face to engage the outer face of the cam 64. Thus when the rail 49 is moved inwardly motion will be transmitted through the intermediate connections to draw the wedge 59 forward to 35 engage the outer face of the wedge 64 and force the bar 65 inward to crowd the point of the switch rail 6 against the rail 2, assuming that the switch point is in proper position, any further movement except to 40 properly align the rails 2 and 6 being prevented by the yielding action of the connection between the lever 54 and wedge 59. If in the travel of a train going from left to right in Fig. 1 for continuous passage along the 45 main line the switch should be incompletely thrown and the rail 6 spaced from the rail 2, a further action of the cam 59 will be permitted to force the bar 65 over so as to properly face or align the rail 6 with the rail 50 2 to shift the switch point to closed position before the wheels of the rolling stock pass the switch point. Similar actions will take place when the switch is thrown for travel between the main and branch lines, only in 55 60 this operation the throwing of the switch will bring the other side of the wedge 64 into position to engage the outer side of the wedge 59, by means of which if the rail 5 is in proper proximity to the rail 1 it will 65 be pressed tightly against said rail with no

greater force than necessary; while if the switch should be in split position the rod 65 will be moved to a greater degree to bring the rail 5 over and face or align it with the rail 1. Hence it will be seen that when a 70 train is running toward the switch points from the main line for continuous travel over the main line or into the branch line the rail 49 will be positively operated before the train reaches the switch to properly face or align the acting rail of the switch point, whichever it may be, to provide a continuous connection and obviate the accidents caused by the running of trains into split switches. The movement 80 of the rail 49 also effects the operation of the trip lever 48 when the switch mechanism is locked in branch line position to trip and release the latch. In such position of the parts the lever 48 engages the hook 47 85 of the dog 43 and on the rearward movement of the engaged arm of this lever motion will be transmitted through the dog to the yoke to return said yoke to the normal position shown in Fig. 5, from that shown in 90 Fig. 6, the pin 41 in this action riding over the V-shaped detent 40 on the latch and tilting said latch to released position, whereby the pin is brought to its normal position 95 in rear of said detent and the throw bar released for retraction in an obvious manner. The adjacent ends of the rails 5 and 49 are spaced a distance less than the distance between the axles of wheels of the trucks of 100 cars and other rolling stock, so that in the travel of a train from the branch to the main line the latch will be tripped as soon as the guard rail is pressed outward by the entrance of the wheels between the same and the rail 1 but the switch will be held thrown by the wheels of the rolling stock until all the wheels have passed beyond the switch, the pressure of the wheels on the guard rails serving to hold the switch thrown until the train has cleared the same and fully entered 105 the main line. It will be observed from the foregoing description that the action of the point facing devices holds the switch rails steady and prevents lateral play thereof as the points are successively engaged and released by the wheels, thus reducing wear and tear on the switch, while the elastic coupling connection between the guard rail and sliding facing cam permits ample movement 110 of the parts to secure a cushioning action in 115 the event of variations of motion due to worn parts, wheels, etc. When the switch is closed as shown in Fig. 1 it will be observed that the guard rail 49 and lever 48 may have free movement without interfering with the parts of the switch throwing and locking mechanism, as the bar 38 may slide over the latch dog 43 without engaging the same. 120 125 130

The other set of devices for facing or

alining the switch point comprises a vertically and longitudinally movable detector bar or rail 67 supported alongside one of the rails in proximity to the switch point 5 and provided with V-shape cam members 68 and vertically and longitudinally movable between suitable guide pins 69 or the like in slotted lugs or brackets 69' fixed to the track (see Fig. 9), so that the rail may 10 be set beyond the points of the cams for longitudinal movement in either direction as it is depressed by the car wheels. The bar is coupled by a connecting rod 70, bell-crank lever 71 and connecting rod 72 with 15 the controller bar 65, so that, according to the position of the detector bar when depressed, the bar 65 will be moved in one direction or the other to crowd the point 5 against the rail 1 or the point 6 against the 20 rail 2 as the case may be, the operation being precisely the same as in the first-mentioned set of devices with the exception that the detector has no control over the releasing lever and no releasing action. It will 25 of course be understood that the detector bar is normally set for movement in one direction and is set for movement in the opposite direction by the throwing of the switch. As shown in Fig. 10, a modified 30 form of detector bar 67' may be employed supported by swinging crank or link arms 68' adapted to perform the function of the cams 68 and guides 69.

From the foregoing description, taken in 35 connection with the accompanying drawings, the construction and mode of operation of my improved switch mechanism will be readily understood, and it will be seen that the invention provides a switch mechanism 40 which is adapted to be operated for the passage of rolling stock in either direction from one line to the other, that the switch can not remain open after passage of the train and will close and remain closed until 45 again actuated so as to prevent accidents to following trains, and that the invention particularly overcomes the well known objections to switches of ordinary construction in effecting the positive closing at all times 50 of a split switch.

In Fig. 11 I have shown a modification in the latch construction wherein the latch 36' is adapted to be held in normal position by a bowed pressure spring 73 jointed at one 55 end thereto, as shown at 74 and having a retaining arm 75, the intermediate portion of said spring 73 being apertured and slidably engaging a guide stem 76 on the latch, on which stem is a coiled spring 77 retained 60 in position and adapted to be tensioned by a nut 78. When the yoke or carriage 31 is moved forward a friction wheel 79 thereon moves from the rear to the front face of the wedge 40 and tilts the latch preliminarily to 65 its locking action. In this motion the roller

79 comes between the wedge 40 and spring arm 75 and lifts said arm against the resistance of the spring 77, whereby the forward end of the spring 73 will be placed under tension to depress the forward end of 70 the latch down and hold it in locking engagement, while the arm 75 will engage and hold the roller 79 from shifting so that the yoke or carriage can not be retracted in a casual manner or until positively operated. 75

While the preferred form of the invention is herein disclosed, it is of course to be understood that changes in the form, construction, proportions and arrangement of parts within the scope of the appended 80 claims may be made without departing from the spirit or sacrificing any of the advantages of the invention.

I claim:—

1. In a railway switch, the combination, 85 with main and branch line rails, of a switch, switch operating mechanism, a means connected with the switch, independent of said operating mechanism, for shifting the switch if split to a fully thrown position, means 90 operative in movement of the switch and controlled by the switch for being acted upon by the first-named means to shift the switch in one direction or the other from the split position, and wheel operated means for 95 actuating the second-named means.

2. In a railway switch, and in combination with main and branch line rails, a switch, a switch throwing mechanism, a controller bar connected with the switch, a cam 100 upon said bar having reverse inclined surfaces, a movable cam having reverse inclined surfaces for coöperation with the surfaces of the first-named cam, said cams being adjusted by the throwing of the switch in one 105 direction or the other to position their surfaces for a positive closing action in one direction or the other of said switch, a wheel operated element, and motion transmitting means between said wheel operated element 110 and said movable cam for actuating the latter.

3. In a railway switch, in combination with main and branch line rails, a switch movable laterally to control communication 115 between the main and branch tracks, a switch throwing mechanism including a latch for holding the switch in thrown position, wheel operated means for releasing the latch, and means actuated by said wheel operated means for shifting the switch to alined position with one or the other of the main rails in the event of the switch being in split position.

4. In a railway switch, and in combination 125 with main and branch line rails, a switch movable between the rails to control communication between the main and branch tracks, a throw rod joining to the switch, a throw bar receiving and inclosing a por- 130

tion of said rod and having an abutment surface, an abutment surface on the rod, a spring disposed about the rod between said abutment surfaces, whereby the rod and bar have a cushioning telescopic connection, the bar having a degree of motion greater than that necessary to effect the throw of the switch by the movement of the rod, latch mechanism for holding the bar projected, 10 means for projecting the bar and throwing the latch mechanism into action, and means for releasing the latch.

5. In a railway switch, a switch throw rod, a throw bar having a telescopic connection with said rod, a spring for transmitting motion from the throw bar to the throw rod, a pivotally mounted latch for locking

the throw bar in projected position, a projection on the latch having reverse inclined surfaces, a plate spring slidably and pivotally mounted intermediate its ends independent of the latch, said spring having a pressure arm connected with the latch and a retaining arm extending over said projection, and a latch controlling member having an engaging member movable over said projection and arranged for coöperation with said retaining arm of the spring. 20 25

In testimony whereof I affix my signature in presence of two witnesses.

MARSHALL L. SHEPHERD.
